UNITED STATES PATENT OFFICE

102,849

DESIGN FOR A TEXTILE FABRIC

George Feinberg, New York, N. Y.

Application August 8, 1936, Serial No. 64,313

Term of patent 3½ years

To all whom it may concern:

Be it known that I, George Feinberg, a citizen of the United States, residing in New York city, county and State of New York, have invented a new, original, and ornamental Design for a Textile Fabric, of which the following is a specification, reference being had to the accompanying drawing, forming part thereof.

The figure is a plan view of a textile fabric showing my new design, with a design unit outlined.

I claim:

The ornamental design for a textile fabric substantially as shown and described.

GEORGE FEINBERG.
